(57) CLAIM

The ornamental design for a beverage opener, as shown and described.

DESCRIPTION

FIG. 1 is a top plan view of a beverage opener showing our new design;

FIG. 2 is a front elevation view of the beverage opener of FIG. 1;

FIG. 3 is a bottom plan view of the beverage opener of FIG. 1;

FIG. 4 is a bottom plan view of a second embodiment of a beverage opener similar to the beverage opener of FIGS. 1-3, 5, and 6 but showing a simulated rugae in a portion of the opener;

FIG. 5 is a left side elevation view of the beverage opener of FIGS. 1-4;

FIG. 6 is a rear elevation view of the beverage opener of FIGS. 1-5; and,

FIG. 7 is a perspective view of the beverage opener of FIGS. 1-3.

The broken lines shown in the figures are for illustrative purposes only and form no part of the claimed design.
